UNITED STATES PATENT OFFICE.

JUSTUS P. SEEBURG, OF CHICAGO, ILLINOIS.

DESIGN FOR AN ORCHESTRION-CASE.

45,655.

Specification for Design.

Patented Apr. 21, 1914.

Application filed February 16, 1914. Serial No. 819,125. Term of patent 14 years.

To all whom it may concern:

Be it known that I, JUSTUS P. SEEBURG, a citizen of the United States, residing at Chicago, in the county of Cook and State of Illinois, have invented a new, original, and ornamental Design for an Orchestrion-Case, of which the following is a specification, reference being had to the accompanying drawing, forming a part thereof.

The figure is a perspective view of an orchestrion case, showing my new design.

I claim:

The ornamental design for an orchestrion case, as shown.

JUSTUS P. SEEBURG.
